UNITED STATES PATENT OFFICE

2,579,981

APPARATUS FOR EFFECTING OR CONTROLLING TRAVERSE OF A BODY BETWEEN OPPOSED WALLS

Harry Spragg, Derbyshire, England, assignor to Markham & Company Limited, Chesterfield, England, a British company

Application June 19, 1945, Serial No. 600,379
In Great Britain June 29, 1944

6 Claims. (Cl. 262—1)

1

According to this invention, an apparatus for traversing or controlling the traverse of a body along and between opposed walls, such as a roof and floor of a mine, comprises a strut longer than the distance between the walls, a carriage on which said strut is oscillatably mounted, means for loading said strut so that it and the carriage are brought into abutting relationship with opposite walls, with the strut in an oblique position, and means for connecting the abovesaid assemblage of parts with said body.

In the case where the apparatus is used for traversing the aforesaid body, for example a mining machine, driving means are arranged to connect the aforesaid strut assemblage with said body, which means are adapted to effect relative reciprocatory movement between said assemblage and body along the line of traverse. It will be appreciated with this arrangement that when the driving means connecting the assemblage with the body effects relative movement during one stroke of reciprocation, the strut will be pivoted against the action of the loading means so as to release the assemblage from the two opposed walls, and thus the assemblage will be moved as a whole relatively to the walls, whereas, when the driving means effects relative movement during the opposite stroke of reciprocation, forces are set up, tending to reduce the obliquity of the strut in relation to the opposed walls, thereby jamming it and the carriage between them, and under these conditions, the body is moved along the walls, and thus the body is traversed step-by-step.

Two or more struts and associated driving means may be provided which are so arranged that the oscillating movements of the struts may take place in any desired sequence, whereby the resultant movement of the body may approximate to uniform.

The aforesaid carriage may be provided with wheels or may comprise a sledge adapted to engage one of the said walls, and pivotally carries said strut, one end of which engages the other wall.

The loading means aforesaid may comprise spring means or a hydraulically or pneumatically operated plunger connected between said strut and said carriage so as to apply a force tending to maintain the strut and the carriage in abutting engagement with said opposite walls. The means for connecting the assemblage with the body may either be secured to the carriage or may be pivotally connected to the strut. This arrangement is particularly suitable when the

2

apparatus is arranged as a safety device for controlling the traverse of the body between the two walls. For example, assuming it is arranged for preventing machines or other objects hauled by ropes or chains from running away due to a breakdown of the haulage system when proceeding along a steep incline. In such an instance, the strut assemblage is either arranged to be trailed behind or pushed in front of the machine or object by means of a connecting-rod, and the arrangement of the connection is such that during normal haulage the force imparted to the strut through the connection tends to move it out of engagement with the wall, whereas, in the event of the failure of the haulage system, there will be a reversal of the force applied to the connecting-rod, tending to jam the strut against the wall and thereby prevent run-away. In an alternative method of utilising the apparatus as a safety device for controlling the traverse of an object, a haulage member may be connected to the strut, so that under normal haulage conditions, it tends to pull the strut free of the walls, and the movement of the strut in this direction is limited by suitable stop means so that a haulage force is then transmitted to the body. Should, however, the haulage system fail, and the body over-run the strut assemblage, the forces are reversed and the strut jams into the wall.

Again considering the apparatus as arranged for traversing the body, for example a mining machine, and having driving means so connecting the aforementioned strut assemblage with the body, as to effect relative movement between these two parts, the said driving means may comprise a crank or eccentric rotatably driven and mounted on one of the parts, and a connecting-rod driven thereby and pivotally connected to the other part. For example, the rotatably driven crank or eccentric may be mounted on said body, and the associated connecting-rod is either pivotally connected to the carriage or to said strut.

In any of the arrangements referred to above, means may be provided for adjusting the effective length of the strut so that the apparatus may be used for different distances between the opposed walls.

The operation may be assisted by the provision of a shoe which is articulately mounted on the free end of the strut.

The following is a description of one form of apparatus for traversing mining machinery along an underground working, reference being made to the accompanying drawings, in which:

Figure 1 is a sectional side elevation of the apparatus;

Figure 2 is a plan view, and

Figure 3 is an end elevation of the strut.

The apparatus comprises two sledges arranged side-by-side at 10 in Figure 1 and each having a flat bottom wall 11 arranged to rest on the mine floor. Each sledge is provided with upturned forward and rearward ends 12, 13 to prevent the bottom walls from digging into the floor. Two upstanding brackets 14 are provided on each sledge extending along the length thereof and inset from the sides of the sledge. Each bracket is reinforced near the centre thereof by two webs 15. Pivotally mounted between the brackets on each sledge is a strut 16 which is of H-section. Secured on either side of the web of each strut and between the flanges is a block 17 having arms 18 extending beyond the end of the strut so as to form a fork-piece 19, as best seen in Figure 3. Each of the brackets is provided with a supporting block 20 which carries a fulcrum pin 21 which extends through holes formed in the blocks 17 and in the web of the strut. A connecting-rod 22 has one end between the arms 18 of the fork-piece 19 and is secured thereto by a pin 23 which passes through holes in said arms. The pin is secured in position by means of a plate 24 secured to one of the arms and projecting into a groove formed in the end of the pin. The extremities of the arms 18 are provided with slots 25 which embrace pins 26 projecting laterally from each side of a tubular shuttle member 27. The shuttle member is reciprocably mounted on a rod 28 fixed between two projections 29 on the bottom of the sledge. Disposed between each end of the shuttle and the nearest abutment is a compression spring 30, the two compression springs being so arranged as to bring the strut at right-angles to the bottom wall of the sledge. Adjustably secured to the upper end of each strut are two members 50 which are secured together at their upper extremities by a spacing block 31. The members 50 are so shaped and dimensioned as to lie flat against the web portion of the H-sectioned strut between the flanges thereof. The web portion of the strut is provided with a number of holes 32 and a hole in each of the members 50 may be brought into register with one of the holes in the web portion. The forked member may be retained in a required position on the strut by means of a bolt 33 which extends through the registering holes and is provided with a wing-nut 34 for clamping the assemblage in position. The spacing block carries a pin 35 projecting on each side thereof and extending through holes in side members 36 formed on the underside of a shoe 37. As in the case of the sledge, the ends of the shoe are bent away from the main plane thereof, as shown at 38, so as to prevent the shoe from digging into the wall. The two sledges are loosely coupled together by a number of inverted channel-shaped members 40 arranged to extend over upstanding parts 41 on the adjacent sledge.

The connecting-rod 22 is connected to a driving element which may either be formed integral with the body which requires to be moved, or may be formed as a separate unit 50 mounted on a sledge 51, as shown in the drawings, which unit 50 may in turn be connected to the body to be moved. The driving means may comprise a compressed air motor 43 which drives an eccentric 44 through suitable gearing 45, com-

pressed air being supplied through pipe 52. The eccentric is encircled by a strap 46 having a connecting-rod 47 secured to a lever-arm 48 on a double-throw crankshaft 49. The crankshaft is provided with two crank-pins for connecting respectively to the two connecting-rods, which crank-pins are arranged 180° apart on the crank-shaft, so that the movement imparted to the body to be traversed approximates to uniform movement.

I claim:

1. Apparatus for traversing a body along and between opposed walls, such as the roof and floor of a mine, comprising two carriages separate from and unsupported by said body arranged to move along one wall, a strut longer than the distance between the walls pivotally mounted on each carriage at a distance away from the lower end thereof so that it is inclined to the vertical, spring means between the lower end of each strut and the carriage so as automatically to maintain the engagement of the carriage and the strut with said walls without imparting up and down thrust to the body, and a reciprocable member on said body pivotally connecting each strut and carriage assemblage to the body and to impart relative reciprocatory movement between each said carriage and the body in out-of-phase relationship.

2. Apparatus for traversing a body along and between opposed walls, such as the roof and floor of a mine, comprising two carriages arranged to move along one wall, a strut longer than the distance between the walls pivotally mounted on each carriage so that it is inclined to the vertical, resilient yielding means automatically maintaining the engagement of each carriage and strut with said walls, driving means on said body comprising a crank shaft having two crank pins disposed at 180°, and connecting rods pivotally attached to the crank pins and to the lower extremities of said struts respectively whereby reciprocatory movement is imparted to the carriages in out of phase relationship.

3. Apparatus according to claim 2, wherein means are provided for adjusting the effective length of each strut.

4. Apparatus according to claim 2, wherein a shoe is pivotally mounted on the opposite end of said strut to said carriage.

5. Apparatus for traversing a body along and between opposed walls such as the roof and floor of a mine comprising two carriages disposed side by side to move along one wall, a strut associated with each carriage, a pivotal mounting on each carriage engaging a strut a short distance from its lower extremity, the length of each of which struts above its pivotal connection together with the distance of the pivotal connection from the bottom of the carriage is greater than the distance between the walls so that each strut is inclined to the vertical, resilient yielding means for automatically maintaining the engagement of each carriage and strut with said walls, driving means on said body comprising a crank shaft having two crank pins disposed at 180°, and connecting rods pivotally attached to the crank pins and to those parts of the struts beneath their pivotal connections with the mounting whereby reciprocatory movement may be imparted to the two carriages in out of phase relationship.

6. Apparatus for traversing a body along and between opposed walls such as the roof and floor of the mine comprising two carriages disposed side by side and arranged to move along one wall, a strut associated with each carriage and having

a slot at its lower end and a pivotal mounting on each carriage engaging one of said struts a short distance from its slotted lower extremity the length of which strut above the pivotal connection together with the distance of the pivotal connection from the bottom of the carriage is greater than the distance between the walls so that each strut is inclined to the vertical, two projections mounted to reciprocate along the carriages and arranged to engage slotted extremities of the 10 struts respectively, spring means arranged on each side of each projection and engaging a fixed part of the carriage so as to maintain the engagement of each carriage and strut with said walls, driving means on said body comprising a crank 15 shaft having two crank pins disposed at 180°, and connecting rods pivotally attached to the crank pin and two pivot pins on the struts disposed between said slot and the pivotal connections with

the mountings whereby reciprocatory movement is imparted to the two carriages in out of phase relationship.
